UNITED STATES PATENT OFFICE.

THOMAS J. WARD, OF LITTLE ROCK, ARKANSAS.

AEROPLANE.

1,283,996.

Specification of Letters Patent.

Patented Nov. 5, 1918.

Application filed May 27, 1918. Serial No. 236,825.

To all whom it may concern:

Be it known that I, THOMAS J. WARD, a citizen of the United States, residing at Little Rock, in the county of Pulaski and State 5 of Arkansas, have invented certain new and useful Improvements in Aeroplanes; and I do declare the following to be a full, clear, and exact description of the invention, such as will enable others skilled in the art to 10 which it appertains to make and use the same.

My invention relates to improvements in aeronautics and more particularly to heavier than air machines employing a plurality of 15 super-imposed planes, a car beneath the planes, a plane extending rearwardly from said planes, and rudders on the rear end of the frame. The principal object of the invention is to provide a machine of this character 20 by whose use a maximum amount of lifting power is obtained without increasing its speed, provision being made whereby any air flowing upwardly from the edges of any plane except the uppermost, will be 25 caught by another plane of greater size.

A further object of the invention is to provide a novel frame structure so constructed as to be easily manufactured and assembled, yet extremely rigid and durable when in use.

With the foregoing general objects in view, the invention resides in the novel features of construction and unique combinations of parts to be hereinafter fully described and claimed, the descriptive matter 35 being supplemented by the accompanying drawings which form a part of this specification and in which:

Figure 1 is a side elevation of the improved aeroplane;

Fig. 2 is a top plan view;

Figs. 3 and 4 are vertical transverse sections on the planes indicated by the lines 3-3 and 4-4 respectively of Fig. 1; and

Fig. 5 is a perspective view showing more 45 particularly the frame structure.

In the drawings above briefly described, the numerals 1, 2 and 3 designate respectively a trio of superimposed planes, all of said planes being of substantially square 50 formation and being preferably curved transversely of the line of flight as shown. The lower-most plane 1 is smaller than the others, and the four edges of the intermedi-

ate plane 2 project beyond the corresponding edges of plane 1, similarly, the upper 55 plane 3, the largest of the trio, projects beyond the edges of the plane 2. By this arrangement, any air flowing upwardly around the edges of the planes 1 and 2, from the lower sides of said planes, will be caught 60 respectively by the planes 2 and 3, so that the machine is given great supporting power on account of the comparatively small loss of "air banks."

The three planes 1, 2 and 3 include rectangular frames 4, 5 and 6 respectively, said frames being connected adjacent their corners and at the centers of their front and rear edges by downwardly diverging standards 7. The standards at the rear 70 corners of the planes depend below the lower frame 4 as seen at 7' and are secured to the sides of a car 8 upon which said lower frame is secured, thus effectively bracing the entire set of planes to said car. 75

The car 8 may be of any suitable construction for carrying the crew of the machine and the necessary material to be used therewith, and the front end of this car is by preference pointed as shown at 8' to offer 80 little resistance to the air. Wheels 9 are shown for use in starting and alighting, but it is obvious that skids, or pontoons might well be employed if desired. The propeller 10 is preferably located between the planes 85 1 and 2 and is shown carried directly by the shaft of an engine 11, but it will be obvious that if desired this engine could well be located in the car 8, in which instance 90 suitable driving connections such as chains would be employed for driving the propeller. The horizontal and vertical rudders 12 and 13 respectively are mounted on the rear end of a frame 14 which extends rearwardly from the planes, and the controls for 95 said rudders may be of any desired type located in the car 8, wires 15 being shown leading from the rudders into the car for connection with said controls.

The frame 14 is of novel construction and 100 includes a lower pair of parallel longitudinal bars 16, an upper pair of similar bars 17, and a central longitudinal bar 18 disposed above the others. The bars 16 extend rearwardly from the frame 4 and the front 105 portions of said bars preferably form the

sides of said frame as illustrated most clearly in Fig. 5; the bars 17 extend rearwardly from frame 5 and the front portions of said bars form plane supporting ribs 17' for the plane in question; and bar 18 projects from frame 6, the front portion 18' of this bar forming one of the plane supporting ribs of the last named frame. By so connecting the front portions of the several 10 longitudinal bars with the superimposed planes, not only is considerable material saved, due to the double use of said front portions, but the bars are held to the plane frames in an extremely rigid manner. The 15 rear ends of the bars 16 are connected by transverse horizontal bars 20 spaced apart longitudinally of the machine and it is to the foremost of said bars 20 that the horizontal rudder 12 is pivoted, said rudder operating 20 between the two bars 20 and the adjacent portions of the longitudinal bars 16. A third transverse horizontal bar 21 connects the rear end of the longitudinal bars 17, vertical bars 22 connect the front bar 20 25 with the bar 21, and an additional vertical bar 23 rises from bar 21 to the rear end of the longitudinal bar 18. The bar 23 carries the rudder 13 as shown for instance in Fig. 1. The necessary truss wires are provided 30 wherever necessary and their particular location may be best determined by the engineer who designs the necessary plans for the manufacture of the craft.

By constructing the machine in the manner shown and described, it will be an extremely rigid device and therefore capable of rather rough usage in all kinds of weather. Also, it will be capable of carrying heavy loads of bombs, aerial torpedoes, 35 etc., and due to the size and relation of the planes, not only the supporting capacity of the machine, but its speed will be extremely high. Since probably the best results are obtained from the details shown and described, these are preferably followed, but 40

within the scope of the invention as claimed, numerous minor changes may well be made.

I claim:

1. An aeroplane comprising a trio of superimposed planes increasing in size from 50 the lower to the upper plane, a pair of longitudinal bars extending rearwardly from each of the lower end intermediate planes, transverse horizontal bars connecting the rear ends of the longitudinal bars of each 55 pair, vertical bars connecting said transverse horizontal bars, a horizontal rudder mounted on the lowermost of said transverse horizontal bars, an additional longitudinal bar extending rearwardly from the center of the 60 upper plane, a vertical bar extending from the rear end of said central longitudinal bar to the uppermost of said transverse horizontal bars, and a vertical rudder mounted on said vertical bar. 65

2. An aeroplane comprising a trio of superimposed planes each having a horizontal frame, said planes increasing in size from the lower to the upper, a lower pair of longitudinal bars whose front end portions form the side bars of the lower frame, an upper pair of longitudinal bars whose front end portions form plane supporting ribs for the intermediate plane, a central longitudinal bar whose front end portions 70 form a central plane supporting rib for the upper frame, all of said bars extending rearwardly from the planes, horizontal transverse bars connecting the rear ends of the longitudinal bars of each pair, vertical bars 80 connecting said horizontal bars, a horizontal rudder mounted on the lowermost of said transverse horizontal bars, an additional vertical bar rising from the uppermost of said transverse bars to said central longitudinal bar, and a vertical rudder mounted 85 on said additional vertical bar.

In testimony whereof I have hereunto set my hand.

THOMAS. J. WARD.
